UNITED STATES PATENT OFFICE.

GEORGE R. PERRY, OF CHICAGO, ILLINOIS, ASSIGNOR TO DIME-NAILER COMPANY, OF THE DISTRICT OF COLUMBIA.

COIN-RECEPTACLE.

1,045,175.

Specification of Letters Patent.

Patented Nov. 26, 1912.

Application filed March 16, 1912. Serial No. 684,183.

To all whom it may concern:

Be it known that I, GEORGE R. PERRY, a citizen of the United States, residing at Chicago, in the county of Cook and State of Illinois, have invented certain new and useful Improvements in Coin-Receptacles, of which the following is a specification.

One of the objects of my invention is to provide a coin receptacle that is of light weight and small dimensions that may be conveniently carried in the vest side pocket.

Another object of my invention is to provide, in a receptacle of this character, openings through which the coins may be seen so that the possessor of the device may at all times be advised at a glance of the number of coins contained in the receptacle, and may, by inspection through said openings observe the general character of the coins.

Another object of my invention is to provide, in a device of this character, means for automatically locking certain of the coins so that they cannot be extracted after they have once been placed in the receptacle beyond the locking means, and to provide other places in the receptacle for coins that may easily be taken therefrom when urgently needed as in cases of emergency. The latter spaces, allotted to the coins, being located between the coin entrance opening and the coin locking means that retains the coins that have passed the locking point.

Another object of my invention is to generally improve the structure of devices of this character.

Other and further objects of my invention will readily appear to persons skilled in the art from a consideration of the following description taken in conjunction with the drawings, wherein;

Figure 1 is an elevation of one side of my receptacle, the opposite side being substantially a duplicate of the side presented in this figure; Fig. 2 is a longitudinal central section taken on line 2—2 of Fig. 1; Fig. 3 is a cross section taken on lines 3—3 of Fig. 1; and Fig. 4 is a fragmentary detail.

In all of the views the same reference characters indicate similar parts.

The device is made, relatively long, flat and narrow, so that it may find ready accommodation in the user's vest pocket. It is composed of two side members, or pieces, 5 and 6, that are substantial duplicates, and each side member is provided with a plu-

rality of perforations 7, that are somewhat smaller than the coin, which the receptacle is to contain. Each of the side members is downturned, as at 8, and outturned at its edges as at 9. The lower side member however, is different from the upper one in that it is turned up at its extreme edge, as at 10, over the edge of the companion side member. And then it is folded down again, as at 11, to provide a joint to hold the two members together. I have found this feature of my structure convenient and cheap of construction but variations of this feature are within contemplation of my invention.

An inturned longitudinal rib, 12, is provided in each of the side members leaving a space larger than the diameter of a coin between the end of the rib and the respective ends of the side members and between this rib and respective outer edge and entirely around the rib is provided a coin channel or raceway, 13. The raceway is of width sufficient to admit the coin, as shown in Fig. 1, wherein a ten cent coin, or dime 15, is shown in place and the relative size of the opening, 16, with relation to the coin, is shown in dotted lines, 16.

Contained between the side members 5 and 6 are two parallel partitions of spring metal, which may be of steel, of bronze, or the like, and which afford the floors of the raceways on the respective sides of the device.

Locking tongues 19, 20, 21, and 22 are cut through each of the sheets 17 and 18 comprising the partitions near the coin entrance end and are bent outwardly so as to form spring latches that will be inwardly deflected and will spring outwardly when the coin is inserted beyond the tongues and thus prevent the coin from being moved in the opposite direction, or returned through the entrance slot. The tongues are located immediately below the parts of the side members 5 and 6 that are not perforated so that they may not be seen. These tongues are positioned so that it would be difficult for one to depress both of the tongues at the same time by insertion of an instrument through the openings and thereby permit the return of the coin, if the presence of the tongues were known. There is another tongue 23, of a similar nature, which is located immediately in front of the coin-inserting-opening provided at the entrance end of the device. This

tongue is also bent outwardly and is intended as a means for frictionally retaining the coin that has been preliminarily inserted through the opening and before it passes the locking tongues, but the coin can be returned through the coin-inserting-opening without interference of the tongue and until after the coin has passed the tongue.

Parts 9, 10, and 11, of the side members 10 are cut away at each end of the device, as shown, to provide slots 24 and 25 through which the coins may be inserted and extracted respectively. The coins are always inserted in the slot 24 and taken from the 15 device through the slot 25.

An opening 26 is made in each of the side members through which to insert an obstruction such as washers to be held by a rivet in the coin path to prevent the coins 20 from passing out through slot 25 until after the rivet has been substantially destroyed and removed.

The perforation, or opening, 27, is made through the sheets 17 and 18, for insertion 25 of the shank of the rivet 28, which may be made of lead, or other similar material. Washers, 29, preferably about the size of the coin, are placed, one on each side, and the rivet is passed through them and it is 30 then compressed to form a head 30 on each side thereby providing a seal for the receptacle.

The inturned rib, 12, has its inner surfaces parallel with the partition wall and rivets 35 31 and 32 may be employed for assisting in holding the side members 5 and 6 together.

The use and operation of the coin holding device is as follows: A coin may be inserted in the slot 24 and is thereby placed immediately over the tongue 23, as when it has 40 been fully inserted, the tongue serves as a means for frictionally retaining the dime, or other coin, in place, but the coin, in cases of emergency, can be removed from this position, out through the entrance opening 24. It is therefore not permanently retained in the receptacle until after it has been pushed 45 beyond the tongues 19 and 20, or the tongues 21 and 22, respectively, as the case may be, and when the coin is in this initial position 50 I will call it an emergency coin, because if an emergency arises it may be quickly extracted and used, as it is not beyond the control of the user until after it passes beyond this position and has been pushed beyond 55 the locking tongues to which I have just referred. In the exemplification shown, the device will contain twenty coins. As it is made for coins of ten cent denomination it 60 will therefore hold two dollars in locked in coins and two emergency coins and each and every one of the coins may be inspected, while it is within the device, through the respective apertures 7. After the coin has 65 passed beyond the emergency position and

it is desired to pass it into the retainer, beyond the locking tongues, it may be moved through the raceway by pressure of the finger applied on the exposed surface of the coin through the apertures 7, and thus it 70 may be moved along the raceway from one aperture to another.

The receptacle is designed to be used in connection with savings banks and for this reason it is advantageous that after the coin 75 has been once inserted in the receptacle it cannot be removed until the seal 28 has been taken away. After the user has filled the receptacle with coins it is then taken to the bank, which is provided with a special tool 80 for removing the seal or other obstruction. After the seal has been taken away the coins may then be emptied from the receptacle through the slot 25, after which another seal is inserted.

I prefer to make the outside members of 85 relatively thin sheet aluminum, and the inside separating sheets 17 and 18, of phosphor bronze or the like. These materials being light and not materially effected by 90 atmospheric conditions.

The device is neat, artistic, and while it is very convenient, it is sufficiently strong to prevent unauthorized persons from extracting the coins therefrom and it is evident that 95 while a ten cent piece is the convenient coin for the purpose of saving, the device may be made suitable for coins of other denominations.

While I have herein described a single 100 embodiment of my invention, for the purpose of complete disclosure, it is evident that many changes may be made within the scope of the appended claims, without departing from the spirit of the invention. 105

What I claim is:—

1. A coin receptacle comprising a side member having its edges down turned and a central longitudinally extending inturned rib to provide, between said rib and sides, 110 coin-raceways; a bottom underlying said side member between which and said side member coin receiving openings are provided for insertion and removal of coins at the respective ends thereof, a removable obstruction in the coin path to said removal opening, and yielding obstructions in the coin path from the insertion opening whereby a coin may be freely inserted but not removed from the receptacle. 115

2. A coin receptacle comprising two substantially duplicate side members having their edges down turned and joined, and each member provided with a central longitudinally extending rib to provide between 125 said rib and respective sides coin raceways, one on each side of each rib, a partition between said side members dividing said raceways each into two separated raceways and between said partition and the end portions 130

of said side members' slots for insertion and removal of coins, are provided, means near the insertion slot preventing return of the coin and means near the removal slot to prevent extraction of the coin.

3. A coin receptacle comprising two substantially duplicate side members, each provided with a plurality of inspection perforations smaller than the coin to be contained therein, and each member having its edges down turned and joined and each member having an inturned longitudinally extending rib, thereby providing coin raceways, in each member, extending entirely around the respective ribs, a separating partition in-

termediate said side members, said side members having their edges cut away near their ends to provide entrance and exit slots for said coins, a spring actuated catch near the entrance slot to prevent return of the coin and an obstruction near the exit slot to retain the coin in the receptacle which said obstruction requires its destruction to permit its removal.

In testimony whereof I hereunto set my hand in the presence of two witnesses.

GEORGE R. PERRY.
